UNITED STATES PATENT OFFICE.

CHRISTOPHER RICHARDSON, OF NEWARK, NEW JERSEY.

IMPROVED APPARATUS FOR TEMPERING STEEL PLATES.

Specification forming part of Letters Patent No. **65,946**, dated June 18, 1867.

To all whom it may concern:

Be it known that I, CHRISTOPHER RICHARDSON, of Newark, Essex county, New Jersey, have invented a new and Improved Oven and Plates for Tempering Steel Plates; and I do hereby declare that the following is a full, clear, and exact description of the construction and operation of the same, reference being had to the annexed drawings, making a part of this specification, of which—

Figure 1 is a plan, Fig. 2 is a side elevation, and Fig. 3 an end elevation, of the oven with plates inside.

The nature of my invention consists in inclosing two metallic plates in a heated chamber or oven, and forcing the two plates, when heated, closely together by a screw, with the saw, or other plate of steel to be tempered, between them. The heat of the plates then reduces the temper of the steel piece embraced, and the pressure prevents any buckling or kinking of the plate.

In my invention a screw is employed to force the two plates together, motion being given to the upper plate by four corner-ties attached to a cross-head riding up and down upon the screw. The screw is operated by a pair of bevel-wheels, and a shaft furnished at the end with a crank, so that an assistant can raise and lower the upper plate while the operator introduces or withdraws the steel to be tempered.

The same letters refer to the same parts in all the drawings.

U is the heated chamber containing the plates, to which A A and B are doors for in-

roducing saws and plates of steel to be tempered. C is the upper tempering-plate. D is the lower tempering-plate, against the bottom of which the pressure-screw abuts. K is the pressure-screw, sustaining the cross-head L, which carries the upper plate C upon the four ties M at the four corners. J J are bevel-gears, which operate the screw K when the shaft I is turned by the crank H. N is a dead-plate to support the flues G G, the brick walls below the doors A A, and the lower plate D. E is a furnace, the heat from which passes over the bridge-wall F, over and between the plates C and D, and then downward, through the flues G G, to the chimney. T is the ash-pit for the furnace. R is the step to support the screw K.

I do not claim that tempering steel sheets or plates under pressure is new, for that has already been done by hydraulic and lever pressure; but

What I do claim, and desire to secure by Letters Patent, is—

1. The application of a screw or screws to produce the required pressure between the heated plates used for tempering.
2. The combination of the plates C and D with the screw or screws K, and the heated chamber U, or their equivalents, when combined and operated substantially as and for the purpose described.

CHRISTOPHER RICHARDSON.
